UNITED STATES PATENT OFFICE

JOHN ROBERT O'DONNELL, OF BROOKLYN, NEW YORK

STAIR CONSTRUCTION

Application filed September 20, 1930. Serial No. 483,172.

The invention relates to stair construction employing both structural steel and reinforced concrete elements as carrying members, all so combined as to produce a more economical and otherwise more satisfactory fireproof stair than other existing types of all steel or composite structures.

The general object of this invention is to refine the type of stair construction disclosed in my previous Patent No. 1,555,750, dated September 29, 1925, so as to effect a substantial saving in time, labor and expense.

The present invention recognizes the purpose of using steel forms in combination with either bent plate strings or pressed steel strings in constructing concrete stairs of two different types. One type is known in the trade as "Econo stairs" having structural steel channel stringers provided with inwardly projecting top and bottom flanges to support the reinforced concrete structure. In this type of stairs the steel forms are used for moulding the concrete, which flows into the channel stringers and forms the steps, risers and soffits.

The other type of stairs is known in the trade as "O. D. Type B" stairs having bent plate strings provided with outwardly projecting top flanges and inwardly projecting bottom flanges to support the reinforced concrete structure. In this type of stairs only the step and riser portions are formed of concrete and the riser portions of the steel forms are often left permanently embedded in the concrete to provide a steel facing for the concrete risers.

The invention thus involves a combined structural steel and reinforced poured-in place stair construction, in which the steel members, besides entering into the permanent structure, act as part of the form-work for supporting members carrying adjustable side forms, extensible riser-forms and floor forms preferably constructed substantially as hereinafter described.

In the accompanying drawings forming a part hereof:

Figure 1 is a vertical horizontal sectional view through a portion of the form-work.

Figure 2 is a top plan view thereof.

Figure 3 is a detail perspective view of a portion of a bent plate stringer supporting a portion of the form-work.

Figure 4 is a cross sectional view through a portion of a stairs showing a pressed steel stringer supporting a portion of the form work.

Figures 5, 6 and 7 are vertical longitudinal sectional views through portions of completed stairs showing different types of stairs constructed in accordance with the invention.

In my previous patent, the side forms and connected risers were secured to the inner sides of the top flanges of the strings after the strings were set in position. This procedure was found tedious and undesirable as it required considerable work in setting and accurately adjusting the side forms, before the risers were connected thereto.

With this invention this objectionable feature is overcome because all of the side forms are secured to and suspended from wooden strips which overlie and are supported on the upper top flanges of the strings. The strips may be laid on the floor and the side forms conveniently secured thereto in their proper spaced relation, thus providing a complete unit which may be readily lifted and secured in position on the top of the strings.

Referring to the drawings in detail, 1 designates the inclined strings which may be bent steel plate, pressed steel sections, or of a built up section. The bent steel plates are disposed with their upper flanges 2 projecting outwardly and their lower flanges 3 projecting inwardly. Between these strings are supported side forms 4, riser forms 5 and an inclined floor-form 6 is secured beneath the side and riser-forms.

The side forms 4 are secured to the inner sides of supporting members such as wooden strips 7 which overlie and are supported on the upper top flanges of the strings 1. When the strips are superimposed on the strings they are secured in position to prevent their displacement, by any suitable clamping means not shown. The side forms are irregular in shape and are designed and positioned so as to lie in the angles between the treads and risers of the stairs to be constructed. The

side forms are made of sheet iron and as shown are held suspended from the strips 7 by nails 8, passing through perforations in the sheet and entering into the sides of the strips 7. Each of the forms 4 is provided with a diagonal slot 9, adjacent to its upper edge, through which passes the threaded end of a bolt 10, secured in the strip 7. A nut 11 is mounted on the threaded end of the bolt and acts to clamp the side form to the inner side of the strip. Through this slotted connection a variable longitudinal adjustment of the form is permitted. After the side forms have been adjusted and secured in their proper spaced relation to each other the nails 8 are then driven through the openings in the sheet 4 and into the strips 7 to hold the forms in their proper set position.

Each of the side forms has welded on the inner side of one end a pair of angle pieces 12 and 13 to provide a pair of brackets to which the riser-form 5 is connected. Bolts 14 projecting from the form 5 adjacent its end and passing through horizontal slots 15 formed in the brackets, together with the nuts 16 on the front end of the bolts, provide a means for securing the riser-form to the side-form in a horizontal adjustable position. This adjusting feature permits variable spacing longitudinally of the riser-forms.

The riser-forms are also made of sheet iron and pressed into the shape shown to provide a horizontal outwardly bulged portion 18, which forms a depression in the face of the risers of the completed stairs to give them a neat and artistic appearance. The riser-forms may be made in various shapes if desired and provided with an outwardly, projecting, straight, horizontal top flange 18' to which may be secured an extension strip to increase the height of the riser if desired.

The floor-form 6 is preferably formed of wood and metal and comprises a pair of section frames 20 held together by tie pieces 21. Each of the frames is covered with a relatively thin sheet of iron 22 which overlaps at the meeting ends of the frames. The section-frames 20 are supported on cross-pieces 23, the ends of which extend beyond the sides of the floor form. The said ends are longitudinally slotted, as indicated at 24, to cooperate with hanger rods 25, which extend downwardly from the strip 7 through the slots 24, beneath which they are provided with nuts 26. Plates, forming brackets 27 are connected to the top of the strips 7 by means of nuts and bolts 28. These plates project respectively beyond the outer sides of the strips 7 and are formed with bolt holes adapted to receive the upper ends of the hanger rods 25. By tightening the nuts 30, the cross-pieces 23 are clamped upward against the strings or against the section frames 20.

When the form-work is set up the usual

reinforcing rods 32 are arranged above the floor and below the riser-forms, see Fig. 4.

In constructing the "Econo" type of stairs, as shown in Fig. 4, it is noted that the side forms 4 are held in spaced relation to the inner sides of the channel steel stringers 1a. When the concrete is poured it will thus flow behind the side forms thus permitting the cheeks, steps, risers, and soffits to be completely molded in one operation.

In constructing the "O. D. Type B" form of stairs, as shown in Fig. 3, the side forms 4 are held against the inner side faces of the bent plate stringers 1, thus providing the means for securing the riser-forms thereto so that when the concrete is poured only the steps, soffits and risers are completely molded in one operation.

As shown in Fig. 5 the riser-form may be utilized to form permanent metal risers 33 and when such is the case, they have secured to their inner face, channel bars 34, which are embedded in the concrete to permanently secure the risers in position.

As shown in Fig. 6, the stairs may be provided with permanent metal noses 36 and as shown in Fig. 7, they may be provided with safety treads 37.

What is claimed as new is—

1. In concrete stair construction, the combination of strings having flanges disposed on their upper edges, said strings constituting part of the form-work and eventually entering into the permanent construction, supporting strips superimposed upon the strings, said strips being longitudinally arranged with respect to the strings and being substantially coextensive therewith, side-forms secured to the strips and riser-forms extending between the strings and secured to said side-forms.

2. In concrete stair construction, the combination of strings having inwardly disposed flanges on their lower end and outwardly disposed flanges on their upper end, and eventually entering into the permanent construction, supporting strips superimposed upon the upper flanges, adjustable side-forms secured to the inner sides of the strips, and riser-forms extending between the strings and secured to said side-forms.

In testimony whereof I have affixed my signature.

JOHN ROBERT O'DONNELL.
